[57] CLAIM

The ornamental design for an ice cream cone air freshener,
as shown and described.

DESCRIPTION

FIG. 1 is a perspective view of an ice cream cone air
freshener embodying my design.

FIG. 2 is a front elevational view thereof; and,

FIG. 3 is a bottom plan view thereof.

The broken-line showing of environmental structure in FIG.
2 is for illustrative purposes only and forms no part of the
claimed design.

The surface(s) or portion(s) of the article not shown in the
drawing or described in the specification form(s) no part of
the claimed design.
